UNITED STATES PATENT OFFICE.

JOHN HARRIS ANDREWS, OF SAN BERNARDINO, CALIFORNIA.

TABLE FOOTBALL GAME.

Application filed September 29, 1926. Serial No. 138,363.

This invention relates to a table foot ball game which is designed to afford amusement and pleasure to the participants and a knowledge of the game.

5 The invention comprises the novel features and combinations hereinafter described and more particularly pointed out and defined in the appended claim.

In the accompanying drawings, which 10 illustrate a preferred embodiment of this invention and in which similar reference numerals refer to similar features in the different views:

Figure 1 is a plan view of a plat containing 15 a simulation of a foot ball field.

Figures 2, 3, 4 and 5 are plan views of cards used to start the game.

Figures 6, 7 and 8 illustrate combinations of cards used after play has started.

20 In Figure 1, there is shown a plat 1, bearing a simulation of a foot ball field marked by lines spaced five yards apart. Between these lines are numbers 1, 2, 3 and 4 upon which the ball 9 is adapted to be placed to indicate the gain past a five yard mark. Thus if the ball which is herein designated as the movable object, is advanced three yards past a five yard line, the object will be placed over the 3.

30 Upon one side of the field there is a series of circles 2 bearing the numerals 1, 2, 3 and 4. A coin or device is adapted to be placed in a circle to denote the "down". Upon the opposite sides of the field, are a series of consecutive numbers 3 which may be used to indicate the yardage gained. Upon the ends of the plat are the goal posts 4.

The game is played with cards. Two decks or series of cards are provided for each side.

40 There is a series of green cards for the offensive side to begin play, which may be termed the "kick off cards". A pair of such cards 5 and 6 are shown in Figures 2 and 4; one indicates a kick off to the 20 yard line, while the other indicates a kick to the 5 yard line.

The defensive side is also provided with a series of green cards 7 and 8, shown in Figures 3 and 5, which may be termed the "return kick-off series" for indicating the play

50 resulting from a kick-off. Thus, green card 7 indicates that a "fair catch" has been made, while green card 8 shows that the kick-off has been returned fifteen yards. It will of course be understood that each series of such green cards will contain any desired number according to the variety of possible

plays. Only two cards of each series have been illustrated.

As soon as the ball has been put in play as above related, its further progress is governed 60 by means of two other series of cards, one series for the offensive side and the other for the defensive side. Certain of such cards are shown in Figures 6 to 8. In order to distinguish these two series, they are preferably of different colors. In the present instance, the series of cards for the offensive side are shown as being white while the series of cards for the defensive side are shown as pink or red. These series of cards are 65 consecutively numbered and each series may contain any desired number of cards according to the variety of plays that might arise. Certain of the pink cards have two numbers as

70 shown in Figures 6 and 7. Thus pink card 31 75 32 responds to either white card 31 or 32, as illustrated in the combination in Figure 6, and pink card $\frac{1}{2}$ responds to either white card 1 80 or 2 as shown in Figure 7. For each white card, there is one or more corresponding pink cards to reduce or cut down the distance that the object is advanced. Thus, pink card 39 corresponds to white card 39 and should be 85 played against such card if possible.

The series of white cards and the series of pink cards are correspondingly numbered. The defensive side must respond with a card bearing the same number as that played by the offensive side if it has a corresponding number in its hand. In the drawing, only a few cards of each series are illustrated. The white cards denote the play. The pink cards, however, control the white cards. For example, if the offensive side plays either white card number 1 or number 2, denoting respectively 2 and 4 yards around right end, the defensive side may play pink card $\frac{1}{2}$ indicating 100 that only one yard has been gained, provided of course that the defensive side has the card $\frac{1}{2}$ in its hand. The pink cards control. 105

It will be noted with reference to Figure 8, that the pink series and white series of cards are at least 39 in number. The others are not illustrated since they may be produced by anyone conversant with the foot ball game in 110 accordance with the disclosure herein.

The game may be played by two opponents

or any number. In starting the game, a coin is tossed up to decide which side shall kick off. The side that kicks off, shuffles the series of "return kick-off" cards while the other side shuffles the kick-off cards. These cards are placed face down upon the table. The side to kick off draws a card from the "kick-off cards" to indicate the play, the side that receives the kick-off then draws a card from the "return kick-off" cards to determine the return play. The object 9 may be placed upon the plat 1 to indicate the position of the ball and a coin may be positioned in number 1 circle to indicate the first down. This is repeated at the start of each game and the beginning of each half, and after each touch-down.

The man or side that receives the kick-off assumes the offensive and the same shuffles the pink cards and deals twelve thereof to the defensive side. The defensive side then shuffles the white cards and deals six to the offensive side. The offensive side will then play one of the six cards dealt. Assume this card to be No. 2, "4 yards right end." If the defensive hand contains cards $\frac{1}{2}$, it will play this card and cut down the gain to one yard. If the defensive hand does not contain this card and cannot meet the play, it stands; the object is then advanced on the plat as per gain and the coin is advanced to record the down. However, if the defensive side cannot play a card, it must discard a card. If it has any doubled numbered card, as for example 31, 32, it must discard it first. After each play, each side will draw a card from its respective deck to maintain the same number as when play started.

If the ball or object is not advanced 10 yards in four downs, it goes to the opposite side. The white and pink cards are again shuffled and dealt, six white cards to the offensive side and twelve pink cards to the defensive side. The offensive side will then play a card, and the defensive side must reply with a card of the same number if contained in the hand, otherwise it must discard a card as before explained.

When a punt is made that goes over the goal line, the ball is put in play on the twenty yard line and goes into possession of the side receiving the punt.

If at any time, the cards are used up by the ball going back and forth while in the possession of the same side, they should be shuffled again. The game may be set at forty minutes, so that each half may be twenty minutes, or any arbitrary time period may be used.

After a touch-down, the ball is brought out to the ten yard line and one play allowed for extra points. This may be a place kick, a pass, line play or a drop kick. The opposite side has one play to stop it.

This game not only affords amusement and pleasure, but it is also instructive in teaching the game. Besides, it greatly improves the memory as it is necessary to remember the discarded cards.

I am aware that many changes may be made, and numerous details of construction may be varied through a wide range without departing from the principles of this invention, and I therefore do not purpose limiting the patent granted hereon otherwise than necessitated by the prior art.

I claim as my invention:

In a table foot ball game, a plat simulating a football field, an object movable on said plat to indicate the results of the plays, a set of offense cards playable by the side having possession of the ball, and a set of defense cards playable by the other side and of a color distinguishing them from the offense cards, each of said offense cards having a legend thereon defining a play and also having indicia thereon corresponding to indicia on one of said defense cards, each of said defense cards having a legend thereon defining a play controlling a play defined by an offense card having similar indicia, and certain of said defense cards having indicia similar to that of two offense cards, so that the defense cards are playable only when their indicia are similar to that on the cards played by the offense.

In testimony whereof I have hereunto subscribed my name.

JOHN HARRIS ANDREWS.
